UNITED STATES PATENT OFFICE.

DARSIE E. EDWARDS, OF CLINTON, MISSOURI, ASSIGNOR OF ONE-THIRD TO CARROLL O. EDWARDS, OF CLINTON, MISSOURI.

SHIRT ANTICREEPER.

Application filed March 3, 1925. Serial No. 12,859.

To all whom it may concern:

Be it known that I, DARSIE E. EDWARDS, a citizen of the United States, residing at Clinton, in the county of Henry and State 5 of Missouri, have invented certain new and useful Improvements in Shirt Anticreepers, of which the following is a specification.

My invention relates to an anticreeping device for preventing shirts from creeping 10 upwardly out of the upper portions of the trousers and causing discomfort to the wearer by becoming wrinkled and untidy in appearance.

A further object is to provide a simple 15 and inexpensive device which will securely and smoothly hold down the shirt without tearing the same, which will readily adjust itself to the movements of the wearer, and which will maintain itself in proper 20 position under varying conditions.

With the above and other objects in view which will hereinafter appear, reference will now be had to the accompanying drawing, in which:

25 Fig. 1 is a side view showing the manner in which the device is worn and the method of holding down the shirt.

Fig. 2 is an elevation of a metallic element and a pad to which it is secured.

30 Fig. 3 is an edge view of the parts shown by Fig. 2.

Fig. 4 is an enlarged fragmentary detail 35 of a leg band and a metallic loop, which latter is slidably connected to the former.

Fig. 5 shows one end of a strap with a fastening device for holding the shirt.

Fig. 6 shows one of the members of a fastening device similar to the one disclosed by Fig. 5.

40 Fig. 7 is a modified form of certain parts.

In carrying out the invention, I employ an adjustable leg band 2, preferably, of web elastic or resilient fabric, which is 45 stitched or otherwise secured at one end to a pad 4 and provided adjacent to its opposite end with a slidable metallic loop 6.

The leg band 2 is folded through the metallic loop 6 as shown by Fig. 4 and secured 50 to a buckle 8, which is slidably mounted upon said leg band 2 for the purpose of taking up or letting out the same to fit the leg of the wearer.

The pad 4 is secured by suitable means 55 such as stitching 10 to the back of a

metallic element 12, which is provided with a hook or stud 14 for engagement by the metallic loop 6. The upper arcuate portion of the element 12 has a slot 16, from which the lower margin 18 is pressed laterally, as indicated by Fig. 3, to admit a strap 20 to said slot 16.

The strap 20 may be made of the same material as the leg band 2 and has a running connection with the slotted portion 16 of the element 12, through which it is folded as shown by Fig. 1. The strap 20 extends upwardly from the metallic element 12 in V-form and is provided at one end with a fastening device 21 consisting 70 of a loop 22 and a member 24, which latter has a hook or stud 26 for engagement by said loop 22. The strap 20 is folded through the slotted lower end of the loop 22 and secured by suitable means such as 75 stitching 28. The fastening member 24 is secured to a tab 30, which in turn is stitched or otherwise secured to said folded end of the strap 20.

The opposite end of the strap 20 is folded 80 through and has a running connection with the slotted lower end 32 of a fastening device 33 which is similar to the fastening device 21 and consists of a loop 34 and a member 36 having a hook or stud 38. The 85 member 36 is secured to a tab 40, which is stitched or otherwise secured to the loop 34.

The end of the strap 20 is connected to a buckle 42, which is slidably mounted on said strap 20 to take up or let out the same 90 according to the distance between the lower portion of the shirt A and the leg band 2.

In practice two of the devices are used, one for each leg and are placed in position by fastening the bands 2 around the legs, 95 to which they are adjusted through the intermediacy of the slidable buckles 8. The fastening devices 21 and 33 at the upper ends of the straps 20 are then secured to the flaps B and C of the shirt by placing 100 the members 24 and 36 against the under surface of said flaps and the members 22 and 34 over the flaps and clamping the same in place by engaging over the members 24 and 36, respectively. The straps 105 20 are then adjusted through the intermediacy of the slidable buckles 42 to the proper length to hold the shirt down so that it can not creep upwardly from the trousers and become wrinkled and uncom- 110

fortable to the wearer. The pads 4 underlying the metallic elements 12 prevent the latter from chafing the legs or rubbing against and wearing out the underclothing.

5 In the modified form shown by Fig. 7, the member 12^a is provided with a roller 16^a, and a cord 20^a is substituted for the strap 20.

Having thus described my invention, 10 what I claim and desire to secure by Letters Patent, is:

1. A device of the character described consisting of a leg band, an element secured thereto and having a slotted arched upper portion, a strap folded into V-form and running through the slotted portion of said element and extending upwardly therefrom, and fastening devices at the upper portions of said strap for detachable en-

gagement with the lower portion of a shirt 20 to keep the same from creeping upwardly.

2. A device of the character described consisting of an element having a slot in the upper portion thereof, a pad stitched to the back of said element, a leg band having one end secured to said pad, fastening devices on said element and the free end of the leg band whereby the latter may be removably attached to the former, a strap folded and running through the slotted portion of said element and extending upwardly therefrom, and fastening devices at the upper portion of said strap for detachable engagement with the lower portion of a shirt. 35

In testimony whereof I affix my signature.

DARSIE E. EDWARDS.
